WINDOW FASTENER

Application filed January 26, 1929. Serial No. 335,289.

Our invention relates to improvements in that type of window fasteners in which a spring-actuated lever is arranged to engage a lug or post, upon the closing of a lower window, or to be engaged by said post upon the closing of the associated upper window, whereby both windows are locked; and the objects of our invention are, first, to produce a strong, durable, and highly efficient, yet comparatively simple and inexpensive, device or appliance for automatically fastening windows when closed, and an appliance which can be readily applied to practically any pair of upper and lower sliding windows; second, to provide the appliance with means for preventing the introduction of an implement between said closed and fastened windows for the purpose of actuating the latch lever to unfasten the windows, said means comprising a plate which is retracted, when said lever is moved into inoperative position, in order not to interfere with the movement of the windows; third, to afford means for drawing the windows tightly together to prevent rattling and the passage of air therebetween or between their meeting-rails; and, fourth, to improve both generally and specifically the construction of window fasteners.

The ordinary window fastener having a spring-actuated latch lever can not be employed to the best or even good advantage where the upper window in a pair has a horizontal parting-rail or parting-rails, because said lever normally extends into the path of such parting-rails and interferes with the movement of the upper window, and must be held with the thumb or finger out of the way while the parting-rails are moved past said lever, or the latter is moved past the former, a more or less difficult task, especially for a woman or child. Moreover, the operator is very liable to forget to hold the latch lever out of the way, and then the parting-rails are injured by more or less violent contact with said lever. These objectional and undesirable liabilities are practically eliminated or avoided when our fastener is employed.

The means whereby is prevented the introduction of a thin implement between the

closed and fastened windows, when consisting of a fixed lip, is not available, when horizontal parting-rails are present in the upper window, if said lip is liable to come into contact with said parting-rails. 55

Other objects and advantages will appear in the course of the following description.

We attain the objects and secure the advantages of our invention by the means illustrated in the accompanying drawings, in 60 which—

Figure 1 is a top plan of a window fastener which embodies a practical form of our invention, showing the guard plate retracted, and the latch lever disengaged from the 65 post, and disposed with its hook in extreme retracted position, and both incapable of contacting with any parting-rail; Fig. 2, is a similar plan showing said lever in engagement with said post, and said plate advanced; Fig. 3, is another top plan illustrating the meeting-rails drawn tightly together and secured by means of the fastener; Fig. 4, is a right-hand side elevation of the fastener with the lever disposed as in Fig. 70 75; Fig. 5, is a top plan, with parts removed and other parts in section, of the element of the fastener which includes the guard plate, showing the relative positions of the members when said plate is retracted; Fig. 6, is a plan similar to that illustrated in Fig. 80 85; Fig. 5, but disclosing the relative positions of said members when said plate is advanced, and, Fig. 7, is a bottom plan of the fastener with the members disposed substantially as in Fig. 3.

Similar reference characters designate similar parts through the several views.

In each of the first three views appear fragmentary portions of the meeting-rail of a lower window sash, at 1, the meeting-rail of an upper window sash, at 2, and glass in the upper sash, at 3, said glass being in section. In Fig. 4, in addition to the aforesaid parts and members, which here are in 90 section, appear one of the side-rails of the lower sash, at 4, the glass therein, at 5, and one of the side-rails of the upper sash, at 6, said glass being in section. Putty for the two pieces of glass 3 and 5 is represented at 7. 95 100

These parts and members are merely typical of windows to which the invention is applicable, and are in no sense to be considered as of a limiting character or nature.

The fastener comprises a hollow base 8, a guard plate 9, and a spring-actuated lever 10 pivotally connected at 11 with said base, together with a hollow base 12 having an upright lug or post 13, and provided with a friction plate 14. The base 8 is mounted on the meeting-rail 1 and secured thereto by means of two screws 15, said base being located with the back edge thereof flush with the back side of said meeting-rail. The base 12 is mounted on the meeting-rail 2 and secured to said meeting-rail by means of two other screws 15, said base being located with its front edge flush with the front side of the meeting-rail.

In shape and size the bases 8 and 12 are generally similar, and said bases are relatively arranged with their corresponding ends in the same vertical planes.

The post 13 has a head 16 which is generally conical in shape, but slabbed off on the front side. The post 13 is thus provided with an under-cut portion to receive between the same and the top of the base 12 a hook 17 at one end of the lever or latch 10. The post 13 is located in the transverse center of the base 12, with the flat side of the head 16 approximately in the same plane with the front edge of said base.

The friction plate 14 is located on top of the base 12 behind the post 13, and has one end secured to said base by means of a rivet 18, said plate here being in the form of a plate spring slightly elevated intermediate of its ends.

The pivot 11 is located approximately in the center of the base 8, and passes down through the latch 10 and the top of said base, including a rectangular lug 19 on said top, to be upset, headed over, or otherwise secured in place under said top. The latch 10 is free to turn on the pivot 11 over the lug 19 and the guard plate 9.

In the base 8 is an arcuate slot 20 struck from the center of the pivot 11. The slot 20 extends from a point adjacent to the back side of the space within the base 8 beyond or forward of a vertical plane which extends longitudinally of said base through the axis of the pivot 11. A pin 21 extends downwardly from the latch 10 into and through the slot 20. Depending from the top of the base 8 inside is a perforated lug 22. The lug 22 is on the opposite side of a vertical plane, which extends transversely of the base 12 and through the center of the pivot 11, to that where the slot 20 is located. The slot 20 is so located that its end, which is adjacent to the back side of the space in the base 8, is approximately in the aforesaid transverse plane. A spring 23 has one terminal at

tached to the lug 22 and the other terminal attached to the pin 21.

Normally the spring 23 retains the pin 21 in the outer or rear end of the slot 20 and against the back side of the base 8, and thereby disposes the latch 10 transversely of said base, as in Figs. 3 and 7. When the latch 10 is swung on the pivot 11, against the resiliency of the spring 23, to locate the pin 21 in the inner or forward end of the slot 20, at which time said latch is disposed lengthwise of the base 8 and substantially as in Fig. 1, said spring at the pin end is moved forward of the axial center of said pivot, and thus retains said latch in the aforesaid position. As soon as the latch 10 is moved to carry the spring 23 rearwardly of the axial center of the pivot 11, said spring acts to swing said latch into its transverse position again.

At the end of the lever 10 opposite to that where the hook 17 is located is an upwardly-extending handle 24.

The guard plate 9 has a transverse slot 25 therein to receive the lug 19, and also a cam slot 26 through which the pin 21 extends before it passes into and through the slot 20. The cam slot 26 is above the slot 20 and opens at its outer end into the outer or rear part, on one side, of the slot 25.

When the latch 10 is in its inoperative position, with the pin 21 in the inner end of the slot 20, said pin is in contact with the inner end of the cam slot 26 and retains the guard plate 9 with its rear edge flush with the rear edge of the base 8, but, when said latch is swung into operative position, said pin travels rearwardly in said two slots, and, owing to the shape of said cam slot, actuates said plate rearwardly with said rear edge thereof projecting some distance beyond said rear edge of said base and onto the front-edge portion of the base 12. There is a central recess 27 in the rear edge of the guard plate 9 to receive the post 13 when said plate is advanced, hence it is the parts of said plate at both ends of said recess that project beyond the base 8 and onto the top of the base 12. The recess 27 is long enough to enable the base plate to clear the post head 16.

Normally the plate 9 is in advanced position, but said plate is retracted and held in retracted position when the latch 10 is actuated into the position shown in Fig. 1, where said latch is held by the spring 23. Then the plate 9 is, of course, out of the path of any horizontal parting-rails in the upper sash, as is also the hook 17. The plate 9 is retracted by the pin 21 when the latter moves forwardly or inwardly in the slot 20 and the cam slot 26. The slot 25 is of sufficient length to permit to take place the necessary movement of the plate 9. The lug 19, the two opposite sides of which are in contact

with the two longitudinal sides of the slot 25, prevents the plate 9 from moving otherwise than in a straight line forward and backward.

5 The pin 21, when in its most forward or outer position, contacts with the back side of the base 8, and, by reason of such contact, relieves the pivot 11 of much of the strain it otherwise would have to sustain from the latch 10 in the forcible engaging of the same with or by the post 13, and while said latch is in engagement with said post and subjected to force exerted thereon by attempted vertical movement of either sash. This is an 10 important feature, because otherwise the pivot 11 might in time become loose and even detached.

The shape, size, and relative proportions of the post 13 and the lock 17 are such that, 20 when said hook, while disposed crosswise of the base 8, is thrust down onto said post, as in lowering the lower window, or said post is thrust up against said jaw, as in raising the upper window, the hook is first 25 forced aside, against the resiliency of the spring 23, and then, by the time the meeting-rails 1 and 2 are even with each other, said hook is actuated by said spring into engagement with said post beneath its 30 head 16, and neither window can be moved to open it. Neither window can be opened because the pivot 11 holds the latch 10 to the base 8 on the meeting-rail 1, and the engagement between the post 13 and said latch 35 causes the latter to be held securely in the base 12 on the meeting-rail 2, or actually in contact with the friction plate 14—see Fig. 2.

If it be necessary or desirable to draw the meeting-rails 1 and 2 closer together, pressure is applied to the handle 24 in the direction to force the hook 17 farther into engagement with the post 13, between the friction plate 14 and the under-cut part of said post, as clearly shown in Figs. 3 and 4. The plate 45 14 holds the hook 17 tightly in position so that there is no danger of the same becoming accidentally disengaged.

In either of the above examples, upon 50 grasping the handle 24 and forcibly swinging the latch 10, against the resiliency of the spring 23, in the direction to disengage its hook from the post, and finally to assume the unlocked or unlatched position illustrated in Fig. 1, the lower window can be 55 raised and the upper window lowered, either or both.

From the foregoing the operation of this fastener will be understood, wherefore we 60 will give below only a brief description of the operation of said fastener as a whole, starting with the parts and members disposed as in Figs. 2, 3, 4, and 7.

To unfasten the windows, the handle 24 is actuated in the direction to swing the hook 17 65 out of engagement with the post 13, and into

completely retracted position, and retract the guard plate 9, leaving the parts and members disposed as in the first view. Either or both windows can now be opened.

To fasten the windows when closed, the latch 10 is moved far enough, from the Fig. 1 position, to carry the spring 23 back of the dead center, and enable said spring to swing said latch crosswise of the base 8, and the lower window is pushed down or the upper 70 window raised, as the case may be, until the jaw 17 snaps into engagement with the post 13. At this time the guard plate 9 is advanced over the front-edge portion of the base 12. The spring 23 does not cause the 75 hook 17 to be drawn into full or complete engagement with the post 13, because of the presence of the friction plate 14, but such full and complete engagement is readily brought about upon grasping the handle 24 80 and forcing the same to the left.

More or less change in the shape, size, construction, and arrangement, of some or all of the parts of this fastener, may be made without departing from the spirit of our invention or exceeding the scope of what is 85 claimed.

We claim:

1. The combination, in a window fastener, with a base attachable to the meeting-rail of an upper window sash, and provided with a post, of a base attachable to the meeting-rail of the associated lower window sash, a guard plate movable on said second-named base, a latch pivotally connected with said second-named base, and having a part to engage and release said post, and cam-operating means to move said plate toward and away from said first-named base as said latch 95 is swung into operative and inoperative position.

2. The combination, in a window fastener, with a base attachable to the meeting-rail of an upper window sash, and provided with a post, of a base attachable to the meeting-rail of the associated lower window sash, and having an arcuate slot therein, a latch pivotally connected with said second-named base, having a part to engage and release said post, and provided with a pin which 100 extends into said slot, and a spring attached at one end to said second-named base and at the other end to said pin.

3. The combination, in a window fastener, with a base attachable to the meeting-rail of an upper window sash, and provided with a post, of a base attachable to the meeting-rail of the associated lower window sash, and having an arcuate slot therein one end of which is adjacent to the back side thereof, a 110 latch consisting in part of a hook adapted to engage and release said post, and provided with a pin which extends through said slot, and is receivable against said back side when 115 in the outer end of said slot, a pivot connect- 120

ing said latch with said second-named base, and a spring attached at one end to said second-named base and at the other end to said pin, whereby the latter assists said pivot in sustaining the strain thereon from said latch.

4. The combination, in a window fastener, with a base attachable to the meeting-rail of an upper window sash, and provided with a post, of a base attachable to the meeting-rail of the associated lower window sash, a latch consisting in part of a hook adapted to engage and release said post, and provided with a pin, a pivot connecting said latch with said second-named base, the latter having therein an arcuate slot cutting a vertical longitudinal plane through said second-named base wherein the axis of said pivot lies, and having one end adjacent to the back side of said second-named base, and a spring attached at one terminal to said second-named base and at the other terminal to said pin which extends through said slot.

5. The combination, in a window fastener, with a base attachable to the meeting-rail of an upper window sash, and provided with a post, of a base attachable to the meeting-rail of the associated lower window sash, provided with a guide lug, and having therein an arcuate slot, a guard plate slidably arranged on said second-named base, and having therein a slot to receive said lug, and a cam slot over said arcuate slot, a latch pivotally connected with said second-named base, consisting in part of a hook adapted to engage and release said post, and provided with a pin extending through said slots, and a spring attached at one end to said second-named base and at the other end to said pin, whereby said plate is advanced and retracted, as said pin is moved in said slots by said latch when swung on its pivot to engage and release said post.

6. A window fastener comprising in combination, a pair of bases for attachment to the meeting rails of a pair of sashes, a post on one of said bases, a latch movable on the other of said bases between a position for engaging said post and a releasing position, a guard plate movable on said other base between a non-guarding position and a guarding position where a portion thereof may overlie a part of said first-named base and connections between said latch and guard plate whereby the guard plate is moved between guarding and non-guarding positions accordingly as the latch is moved between post-engaging and releasing positions.

7. A window fastener comprising in combination, a pair of bases for attachment to the meeting rails of a pair of sashes, a post on one of said bases, a latch movable on the other of said bases between a position for engaging said post and a releasing position, a guard plate movable on said other base be-

tween a non-guarding position and a guarding position where a portion thereof may overlie a part of said first-named base and connections between said latch and guard plate whereby the guard plate is moved between guarding and non-guarding positions accordingly as the latch is moved between post-engaging and releasing positions, and a spring for yieldingly holding said latch in releasing position and in post engaging position.
